UNITED STATES PATENT OFFICE.

PAUL N. BOSSART, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 29, 1926. Serial No. 84,588.

My invention relates to railway traffic controlling apparatus, and particularly to apparatus of the type comprising train carried governing means co-operating with devices 5 located at intervals along the trackway. More particularly my present invention relates to the train carried portion of such apparatus.

I will describe one form of apparatus embodying my invention, and will then point 10 out the novel features thereof in claims.

The accompanying drawing is a diagrammatic view illustrating one form of railway traffic controlling apparatus embodying my 15 invention.

Referring to the drawing, the reference character 1 designates a track rail of a stretch of railway track traversed by trains one of which is indicated diagrammatically 20 at V. Suitably mounted on train V is a receiver A comprising a magnetizable core 2 having the shape of an inverted letter U. This core is provided with two windings 3 and 4. Located also on the train is a relay R, 25 and a magnet D which controls the usual brake mechanism on the train so that the brakes are applied when the magnet is de-energized.

Current is at times supplied to windings 30 3 and 4 from a suitable source of direct current such as a battery J. A circuit for winding 4 may be traced from battery J, through wires 8 and 9, front contact 10 of relay R, wires 11 and 12, winding 4 of receiver A, 35 wires 13 and 14, winding of magnet D, and wires 15 and 16, back to battery J. It will be seen that this circuit is closed only when relay R is energized, under which condition magnet D is energized to prevent an automatic 40 application of the brakes. A circuit for winding 3 may be traced from battery J, through wires 8, 9 and 17, front contact 18 of relay R, wires 19 and 20, winding of relay R, wire 21, winding 3 of receiver A, wires 22 and 45 14, winding of magnet D and wires 15 and 16, back to battery J. It will be seen that the circuit just traced is a stick circuit for relay R by means of which the relay is maintained in its energized condition after contact 18 has once been closed. Windings 3 and 4 are so placed on the core and so connected in these circuits that the magnetic fluxes created by

currents in the windings are in opposition. Preferably winding 4 has more turns than winding 3 as indicated in the drawing. 55

The reference character K designates a circuit controller comprising two normally open contacts 23 and 24. This circuit controller is operated by a pneumatic relay G comprising a chamber 27, one wall of which is a flexible 60 diaphragm 25. Chamber 27 is connected with the atmosphere through a restrictive orifice 28. Fluid pressure, usually air, is at times supplied to chamber 27 by an acknowledging valve H. When valve H is in its normal position, in which it is illustrated in the drawing, an acknowledging reservoir 30 is connected through pipe 31 with a source of fluid pressure not shown in the drawing. When valve H is reversed, however, reservoir 70 30 is disconnected from pipe 31 and is connected with chamber 27 through pipe 29. The pressure thus supplied to the relay G forces diaphragm 25 downwardly against the bias exerted by a spring 26, thereby closing 75 contacts 23 and 24, which are operatively connected with the diaphragm 25. The pressure thus supplied to chamber 27 is gradually dissipated to atmosphere through orifice 28 so that after a time interval the spring 26 moves 80 diaphragm 27 upwardly to its original position thereby re-opening contacts 23 and 24 of circuit controller K.

A signalling device designated by the reference character S is controlled by circuit controller K. In the form here shown this device is a single stroke electric bell and is provided with a circuit which may be traced from battery J, through wires 8, 32 and 32^a, contact 23 of circuit controller K, winding of bell S, 90 wires 34, 35 and 12, winding 4 of receiver A, wires 13 and 14, winding of magnet D, and wires 15 and 16, back to battery J. It will be seen from the drawing that front contact 10 of relay R is included in a shunt path around the bell S and contact 23. This shunt path passes from wire 8, through wire 9, front contact 10 of relay R and wire 11 to wire 12. It is manifest, therefore, that when circuit controller K is closed, bell S will be operated 95 provided the shunt path including contact 10 is open, that is, provided relay R is de-energized, but that the bell will not be operated if contact 10 is closed. 100

Associated with the bell S is a switch 37 controlled by the operating mechanism of the bell so that this switch is closed only when the bell is energized.

5 When switch 37 and contact 24 of circuit controller K are both closed, current flows from battery J, through wires 8 and 32, contact 24 of circuit controller K, wire 36, switch 37, wires 38 and 20, winding of relay R, wire 21, winding 3 of receiver A, wires 22 and 14, winding of magnet D, and wires 15 and 16, back to battery J. When this circuit is closed, current is supplied to relay R and this circuit therefore comprises a pick-up circuit for energizing the relay.

As shown in the drawing, relay R is energized, so that current is flowing through relay R, winding 3, winding 4, and magnet valve D. Acknowledging valve H is in its 20 normal position so that reservoir 30 is charged with fluid pressure, and circuit controller K is open, because diaphragm 25 of relay G occupies its upper position. The bell S is therefore de-energized and switch 37 is 25 open.

The train carried apparatus thus far described is suitable for co-operation with trackway devices, one of which is illustrated at B in the drawing. This device, in the form 30 here shown, is a trackway inductor comprising a magnetizable core 5 provided with a winding 6. A plurality of the inductors B are located at intervals along the trackway and are so disposed that as the train V moves 35 along the trackway, core 2 of the receiver A passes successively over the cores 5 of the trackway inductors B.

Means are provided for at times short circuiting the winding 6 of each trackway inductor. As shown in the drawing, when switch 7 is closed, winding 6 is short circuited, thereby increasing the effective reluctance of the core 5 to a rapid change of flux. In actual practice the switch 7 will 45 usually be controlled by traffic conditions in advance.

In explaining the operation of the apparatus as a whole, I will first assume that the train passes a trackway inductor B when the winding 6 thereon is short-circuited. As the receiver A passes this inductor the core 5 of the inductor will be included in the magnetic circuit of the core 2 of the receiver. Due, however, to the large effective reluctance of 50 the core 5 to rapid changes in the flux therethrough, there will be substantially no change in the flux created in core 2 by windings 3 and 4. When the train passes a trackway inductor having its winding short-circuited therefore, the train carried apparatus is not affected.

I will now assume that switch 7 of the trackway inductor is open and that the train V passes the inductor. As the core 2 passes 65 over core 5, the reluctance of the magnetic

circuit including core 2 is materially decreased. The magnetic flux created by winding 4 which links winding 3 is therefore substantially increased. This increasing magnetic flux creates in the circuit including 70 relay R a single cycle of alternating current one half of which is opposite in direction to the current supplied to relay R by battery J and is sufficient in magnitude to cause this relay to become de-energized. The de-energization of relay R interrupts all of the circuits for magnet D and so causes an automatic application of the brakes. At the same time the 75 opening of front contact 18 of relay R breaks the stick circuit for this relay. The other circuit for the relay is open at circuit controller K and it follows that after the receiver A has 80 passed the trackway inductor B the relay R will remain in its de-energized condition.

The engineman may forestall an automatic 85 brake application by proper manipulation of the acknowledging valve H. To accomplish this result, he operates valve H just before the train passes the inductor. Reservoir 30 is then connected with chamber 27, and circuit controller K is closed. This has no effect on signal S because front contact 10 of relay R is still closed and signal S is therefore short-circuited. When the train passes the inductor however, relay R becomes de-energized as 90 explained hereinbefore. The opening of front contact 10 breaks the shunt path around bell S and this bell therefore operates. It is manifest that bell S will not ring unless the relay R actually opens and then only if the engineman has actuated circuit controller K. The operation of the bell therefore informs 95 the engineman that the train carried apparatus has functioned properly. The energization of bell S closes switch 37, and if circuit controller K is still closed, current is supplied to relay R over front contact 24 of circuit controller K and switch 37. By the time this 100 happens the receiver A will have passed the inductor B and relay R will again become energized. Magnet D then becomes energized to prevent an automatic application of the 105 brakes. As soon as front contact 10 of relay R closes, bell S is shunted and switch 37 opens. Relay R is now held in its energized condition 110 by its stick circuit, although its pick-up circuit is broken at switch 37.

In actual practice the brake applying mechanism controlled by magnet D has a sufficient 115 time interval to insure that the brakes will not be applied during the brief de-energization of relay R which takes place if the engineman acknowledges as the train passes a trackway inductor.

After the expiration of the time interval required for the fluid pressure in chamber 27 to become dissipated to atmosphere circuit controller K opens and the apparatus then occupies its original condition. It should be particularly pointed out that should the engine- 125

man operate circuit controller K too soon, this circuit controller will re-open before the switch 37 closes and it will therefore be impossible to pass the trackway inductor without a brake application unless the valve H is operated again.

From the explanation of the apparatus just made it will be seen that when relay R becomes de-energized the circuit for winding 4 of receiver A is broken. The winding 4 has a considerable amount of inductance and under certain conditions it may happen that the sudden interruption of the current through this winding might cause injurious sparking at contact 10. The winding of magnet D also has considerable inductance and since this winding is connected in series with winding 4 its effect is added to winding 4 in causing sparking at contact 10.

In order to prevent this sparking I prefer to connect a resistance in parallel with winding 4 of receiver A and the winding of magnet D. I have discovered that an asymmetric unit is a particularly desirable form of resistance for this purpose. One form of asymmetric unit which is peculiarly adapted for this use is the copper oxide rectifier disclosed in an application for Letters Patent of the United States Serial No. 1,111, filed January 30, 1925, by Lars O. Grondahl, for uni-directional current carrying devices. The asymmetric unit indicated diagrammatically in the drawing at 40 is connected in parallel with winding 4 and the winding of magnet D. As the contact 10 of relay R opens the collapse of the magnetic field surrounding winding 4 creates a surge of current which is shunted away from contact 10 through a circuit which may be traced from the right-hand terminal of winding 4 through wires 13 and 14, winding of magnet D, wires 15 and 41, asymmetric unit 40, wires 39, 35 and 12, back to the left-hand terminal of winding 4. The asymmetric unit 40 is so arranged that it offers a smaller resistance to current flowing in the direction just traced than to current flowing in the opposite direction through this circuit. It follows, therefore, that the asymmetric unit offers a high resistance to current from battery J which would ordinarily flow through the unit when contact 10 of relay R is closed. I have discovered that with an asymmetric unit connected as here shown and described, there is substantially no sparking at contact 10 when this contact opens.

One advantage of the apparatus embodying my invention is that only one relay is used on board the train in place of a plurality of relays which have been used for similar purposes in railway traffic controlling apparatus suggested.

Although I have herein shown and described only one form of railway traffic controlling apparatus embodying my invention, it is understood that various changes and

modifications may be made therein within the scope of the appended claims without departing from the spirit and scope of my invention.

Having thus described my invention, what I claim is:

1. In railway traffic controlling apparatus comprising a train carried magnetizable core provided with two windings and means in the trackway for at times varying the reluctance of the magnetic circuit through said core, the combination of a relay, a magnet for controlling the brakes on the train, a source of direct current, means for connecting one terminal of said source with a terminal of one said winding through said relay and a front contact of the relay, means for connecting said one terminal of the source with a terminal of the remaining winding through a front contact of said relay, and means for connecting the free terminals of both said windings with the remaining terminal of said source through said magnet.

2. In railway traffic controlling apparatus comprising a train carried magnetizable core provided with two windings and means in the trackway for at times varying the reluctance of the magnetic circuit through said core, the combination of a relay, a magnet for controlling the brakes on the train, a source of direct current, a circuit for said magnet including one of said windings and controlled by a contact of said relay; a circuit for said relay including said source, the other said winding, and a front contact on said relay; a manually controlled circuit controller; a normally open switch arranged to be closed when said circuit controller is operated provided said relay is open; and a second circuit for said relay including said switch, said source, and said other winding.

3. In railway traffic controlling apparatus comprising a train carried magnetizable core provided with two windings and means in the trackway for at times varying the reluctance of the magnetic circuit through said core, the combination of a relay, a magnet for controlling the brakes on the train, a source of direct current, a circuit for said magnet including one of said windings and controlled by a contact of said relay; a circuit for said relay including said source, the other said winding, and a front contact on said relay; a manually controlled circuit controller, a normally open switch arranged to be closed when said circuit controller is operated provided said relay is open; and a second circuit for said relay including said switch, said source, said other winding, and a contact of said circuit controller.

4. In railway traffic controlling apparatus comprising a train carried magnetizable core provided with two windings and means in the trackway for at times varying the reluctance of the magnetic circuit through said core, the combination of a relay, a magnet for

controlling the brakes on the train, a source of direct current, a circuit for said magnet including said source and one of said windings and controlled by a contact of said relay; a circuit for said relay including said source, the other said winding, and a front contact on said relay; a manually controlled circuit controller, and a signalling device arranged to be operated when said circuit controller is operated provided said relay is open.

5. In railway traffic controlling apparatus comprising a train carried magnetizable core provided with two windings and means in the trackway for at times varying the reluctance 15 of the magnetic circuit through said core, the combination of a relay, a magnet for controlling the brakes on the train, a source of direct current, a circuit for said magnet including said source and one of said windings and controlled by a contact of said relay; a circuit for said relay including said source, the other said winding, and a front contact on 20 said relay; a manually controlled circuit controller, and a signalling device controlled by said relay and by said circuit controller.

6. In railway traffic controlling apparatus comprising a train carried magnetizable core provided with two windings and means in the trackway for at times varying the reluctance 30 of the magnetic circuit through said core, the combination of a relay, a magnet for controlling the brakes on the train, a source of direct current, a circuit for said magnet including said source and one of said windings and controlled by a contact of said relay; a circuit for said relay including said source, the other said winding, and a front contact on 35 said relay; a manually controlled circuit controller, a normally open switch arranged to be closed when said circuit controller is operated provided said relay is open, and a shunt around said front contact controlled by said switch.

7. In railway traffic controlling apparatus comprising a train carried magnetizable core provided with two windings and means in the trackway for at times varying the reluctance 45 of the magnetic circuit through said core, the combination of a relay, a magnet for controlling the brakes on the train, a source of direct current, a circuit for said magnet including said source and one of said windings and controlled by a contact of said relay; a circuit for said relay including said source, the other said winding, and a front contact on 50 said relay; a manually controlled circuit controller, a normally open switch arranged to be closed when said circuit controller is operated provided said relay is open, and a shunt around said front contact controlled by said switch and by said circuit controller.

8. Railway traffic controlling apparatus comprising a relay, a magnet for controlling the brakes of a train, a circuit for normally 55 energizing said relay over its own front contact, a circuit for said magnet including a contact of said relay, means located partly in the trackway for at times de-energizing said relay, a manually controlled circuit controller, a normally open switch arranged to be closed 70 when said circuit controller is operated provided said relay is open, and a shunt circuit around said front contact including said switch and a contact of said circuit controller.

9. Railway traffic controlling apparatus 75 comprising a relay, a magnet for controlling the brakes of a train, a circuit for normally energizing said relay over its own front contact, a circuit for said magnet including a contact of said relay, means located partly in the 80 trackway for at times de-energizing said relay, a normally open circuit controller, manually operable means effective when operated to close said circuit controller for an interval of time, a normally open switch arranged to 85 be closed when said circuit controller is closed provided said relay is open, and a shunt circuit for said front contact including said switch and a contact of said circuit controller.

10. Railway traffic controlling apparatus 90 comprising an inductive winding on a train, a circuit for said winding including a source of direct current and a normally closed contact, means for at times opening said contact, and an asymmetric unit connected in 95 parallel with said winding.

11. Railway traffic controlling apparatus comprising an inductive winding on a train, a circuit for said winding including a source of direct current and a normally closed contact, means for at times opening said contact, and a copper oxide rectifier unit connected in parallel with said winding. 100

12. Railway traffic controlling apparatus comprising an inductive winding on a train, 105 a circuit for said winding including a source of direct current and a normally closed contact, means for at times opening said contact, and an asymmetric unit connected in parallel with said winding and offering a lower resistance to the transient current flowing 110 through the unit when said contact is opened than to the steady current flowing through the unit from said source when said contact is closed. 115

13. In railway traffic controlling apparatus comprising a train magnetizable core provided with two windings and means in the trackway for at times varying the reluctance of the magnetic circuit through said core, the combination of a relay, a magnet for controlling the brakes on the train, a circuit for said relay including a contact on the relay and one of said windings, a circuit for said magnet including the other said winding and a contact of said relay, and an asymmetric unit connected in parallel with said magnet and said other winding. 120

14. In railway traffic controlling apparatus comprising a train carried magnetiz- 125

able core provided with two windings and means in the trackway for at times varying the reluctance of the magnetic circuit through said core, the combination of a relay, a magnet for controlling the brakes on the train, a source of direct current; a circuit for one of said windings including said source, said magnet, and a front contact of said relay; a circuit for the other said winding including said source, said magnet, the winding of said relay, and a front contact of the relay.

15. In railway traffic controlling apparatus comprising a train carried magnetizable core provided with two windings and

means in the trackway for at times varying the reluctance of the magnetic circuit through said core, the combination of a relay, a magnet for controlling the brakes on the train, a source of direct current; a circuit for one of said windings including said source, said magnet, and a front contact of said relay; a circuit for the other said winding including said source, said magnet, the winding of said relay, and a front contact 20 of the relay, and an asymmetric unit connected in parallel with said one winding.

25 In testimony whereof I affix my signature.

PAUL N. BOSSART.
